GAS LIFTING DEVICE FOR FLOWING
MULTIPLE ZONE WELLS

Edwin O. Bennett, Houston, Tex., assignor to
Continental Oil Company, Ponca City, Okla.,
a corporation of Delaware

Application July 4, 1945, Serial No. 603,140

1 Claim. (Cl. 103—1)

1 This invention relates as indicated to an improved method for producing multiple zone wells, i. e., wells which intercept a plurality of superposed vertically spaced producing zones at least one of which is not under sufficient pressure to raise the oil therefrom to the ground surface.

When the pressure in a producing zone is such that it is insufficient to raise the column of oil in the well to the surface of the ground, such a well can be caused to continue production without pumping if air or some other gas is introduced into the oil column in the well sufficiently below the surface of the ground so as to decrease the weight of this oil column sufficiently so that it will be forced upwardly by the pressure available in the producing zone. While this expedient has been utilized in wells producing from a single zone, it has never been accomplished successfully in wells intercepting a plurality of zones and especially where it is necessary to maintain separate the oil produced from each zone.

It is, accordingly, a principal object of my invention to provide a method capable of achieving the foregoing desirable result.

Other objects of my invention will appear as the description proceeds.

To the accomplishment of the foregoing and related ends, said invention then comprises the features hereinafter fully described and particularly pointed out in the claims, the following description and the annexed drawings setting forth in detail certain illustrative embodiments of the invention, these being indicative, however, of but a few of the various ways in which the principle of the invention may be employed.

In said annexed drawing:

Fig. 1 is a diagrammatic, broken, vertical section through a portion of a well intercepting two producing zones and illustrating one embodiment of the method comprising my invention;

Fig. 2 is a view similar to Fig. 1 but showing an alternative mode of operation of my improved process; and

Figs. 3 and 4 are, respectively, views similar to Figs. 1 and 2 but showing alternatively still another modification of my invention.

Referring now more specifically to the drawing and more especially to Fig. 1, there is here illustrated a single well provided with a casing generally indicated at 1, which intercepts two vertically spaced superposed producing zones generally indicated at 2 and 3. The casing 1 has arranged preferably coaxially therein two strings of tubing generally indicated at 4 and 5, whereby there are provided within the case

portion of the well three substantially independent columns.

Positioned in the outer column, i. e., in the space between the tubing 4 and the casing 1, is an annular packer 6 of conventional design, and similarly, in the intermediate column between the tubing 4 and 5 is another packer 7, likewise of conventional design. Since packers of this character are available and well known to those familiar with the art, they have been illustrated diagrammatically.

In the embodiment of my invention illustrated in Fig. 1, the casing and each of the tubings is perforated in each of the producing zones, although it should be noted that the perforations in the tubing 4 may be at any point within or above the producing zone 2 and the perforations in the tubing 5 may be at any point within or above the producing zone 3.

20 A suitable gas, such as air, carbon dioxide, natural gas, and the like, may be introduced under pressure by conventional means not shown into the intermediate column between the tubings 4 and 5. Such gas under pressure will be bled through the perforations in tubings 4 and 5 into the producing columns as illustrated, and such gas reducing the weight of the rising column of oil in the producing zone will make possible the flowing of the column under the pressure available in the producing zone with which it is in communication.

25 When a situation is encountered in the field where only one of the producing zones, as for example the lowermost, lacks sufficient pressure to raise the oil to the surface of the ground, then an expedient such as is illustrated in Fig. 2 may be employed in which only the tubing 5 is perforated and accordingly gas is admitted to only that column which is supplied by the producing zone in question. Here again, the perforations in the tubing 5 may be at any point within or above the producing zone 3, the location of such perforations being determined largely by the amount of pressure available in the producing zone and the depth of such zone.

30 The expedient illustrated in Figs. 3 and 4 employing the same concentric arrangement of casing and tubing is adapted particularly for alternative operation of the two producing zones; the expedient illustrated in Fig. 3 operating the upper zone 2 while the lower zone 3 is broken and the expedient illustrated in Fig. 4 producing the lower zone 3 where the upper zone 2 is broken.

35 In carrying out the modification of my invention as illustrated in Figs. 3 and 4, valved packers

generally indicated at 8, 9, 10 and 11 are provided as well as a conventional packer 12. Valve packers 8, 9, 10 and 11 are of conventional design and adapted to be actuated by wires which extend upwardly in the column in which such valve packers are situated. For example, wire 13 is arranged to and connected with valve packer 8 for operation of the latter; wire 14 is connected with both valve packers 9 and 10 for simultaneous operation thereof; and wire 15 is connected with packer 11 for operation thereof.

When it is desired to produce only the upper zone, as illustrated in Fig. 3, valve packer 8 will be opened and the remaining valve packers will be closed. Air or other gas under pressure is introduced to the center column, i. e., into the tubing 5 from which it is bled through the perforations in such tubing and the perforations in the tubing 4 into the outermost column from which the upper zone 2 is proposed. When it is desired to produce the lower zone 3 and block off the upper zone 2, then the valve packer 8 will be closed and the remaining valve packers will be opened whereupon the air or other gas from the tubing 5 will be admitted to the column between the tubings 4 and 5 thereby raising the oil column in such space as produced from the lower zone 3. Generally an arrangement such as illustrated in Fig. 4 will be operative without the provision of any additional valving means; however, should the pressure in the upper zone 2 be sufficient to drive the oil from such zone into the intermediate column, this can be prevented by suitable available valving means effective to shut off the perforations in the tubing 5 in the area of the upper zone 2.

From the foregoing description, it will be observed that I have provided a method whereby a single well intercepting a plurality of producing zones may be operated so as to provide a gas lift for the stream produced from each zone while maintaining separate production from each zone. Detailed illustration or description of the apparatus necessary has not been given since all of the described apparatus required for the per-

formance of the several steps is old and well known in the art and familiar to those skilled in the art.

Other modes of applying the principle of the invention may be employed, change being made as regards the details described, provided the features stated in the following claim or the equivalent of such be employed.

I therefore particularly point out and distinctly claim as my invention:

Means for flowing oil from two vertically spaced, superposed producing zones in a bore hole comprising a casing arranged within said bore hole provided with means of communication with each of said producing zones, a first string of tubing arranged inside the casing, packer means arranged for sealing the annular space between said casing and said tubing at a point between said two producing zones, valved packer means arranged in the annular space between said casing and said tubing at a point above the upper producing zone, means communicating said first string of tubing with said casing at each of said producing zones, a second string of tubing arranged inside of said first string of tubing, valved packer means arranged in the annular space between said first and second strings of tubing at a point above the upper producing zone and at a point between the two producing zones, means communicating said second string of tubing with said first string of tubing at each of said producing zones, valved packer means in said second string of tubing between said two producing zones, and means for actuating said valved packer means.

EDWIN O. BENNETT.
